UNITED STATES PATENT OFFICE.

WALTER F. STIMPSON, OF DETROIT, MICHIGAN, ASSIGNOR TO STIMPSON SCALE AND MANUFACTURING COMPANY, OF NORTHLVILLE, MICHIGAN, A CORPORATION OF MICHIGAN.

DESIGN FOR A SCALE-BASE.

41,350.

Specification for Design.

Patented May 2, 1911.

Application filed October 30, 1909. Serial No. 525,598. Term of patent 14 years.

To all whom it may concern:

Be it known that I, WALTER F. STIMPSON, a citizen of the United States of America, residing at Detroit, in the county of Wayne, and State of Michigan, have invented a new, original, and ornamental Design for a Scale-Base, of which the following is a specification, reference being had to the accompanying drawing, forming a part thereof.

The figure is a perspective view of a scale base, showing my new design.

I claim:

The ornamental design for a scale base, as shown.

WALTER F. STIMPSON.
